UNITED STATES PATENT OFFICE.

DENNIS A. WHITNEY, OF HOLLAND, NEW YORK, ASSIGNOR OF ONE-HALF
TO WILLIAM D. HUNTINGTON, OF HOLLAND, NEW YORK.

TELEGRAPH-SOUNDER.

No. 845,153.

Specification of Letters Patent.

Patented Feb. 26, 1907.

Application filed November 15, 1906. Serial No. 343,553.

To all whom it may concern:

Be it known that I, DENNIS A. WHITNEY, a citizen of the United States, residing at Holland, in the county of Erie and State of New York, have invented certain new and useful Improvements in Telegraph-Sounders, of which the following is a specification.

My invention relates to improvements in telegraph-sounders, and particularly to the resonator or sound-amplifying device for use in connection with telegraph instruments in general.

The main object of my invention is to provide means for amplifying or increasing the sound made by the ordinary main-line relay, so that the use of a local sounder will not be necessary and the messages may be read direct from the relay.

Further objects of my invention are to produce a resonator for telegraph instruments which may be readily applied to the instruments now in common use, which is adjustable to suit different conditions and requirements, and which will render the faint "clicks" ordinarily produced by such instruments clearly audible and distinct sounds, further objects being to produce such a device in simple and compact form thoroughly practical and efficient.

To attain the desired objects, the invention consists, primarily, of a pair of drums or resonating-chambers between which the armature of the telegraph instrument is adapted to vibrate, said drums being of such construction to increase or amplify the sound produced by such vibrations, and the invention further comprises certain other novel features of construction, combination, and arrangement of parts, substantially as herein set forth.

Figure 1 is a side elevation of my invention as applied to the familiar and well-known type of telegraph instrument known as the "main-line relay." Fig. 2 is a front end elevation of the same. Fig. 3 is a top plan view of the instrument with my improvements. Fig. 4 is a longitudinal sectional view of the complete apparatus, and Fig. 5 is a sectional view taken through one of the resonating-chambers on line 5-5 of Fig. 4.

The main-line relay illustrated in the accompanying drawings is of the usual and ordinary construction, comprising a base 1, a

pair of magnets 2, a bracket 3 for supporting the forward end of the magnets, an armature 4, pivoted to vibrate in close proximity to the poles of said magnets, a post 5, a spring-adjusting bar 6, adjustably secured in the post, a retractile spring 7, connected to the armature, and a thumb piece or member 8 for adjusting the tension of the retractile spring. The rear ends of the magnets are connected by a yoke 9, from which extends the bolt 10. A supporting-post 11 is mounted near the end of the base, and through an opening provided for that purpose in the post is passed the bolt 10, a thumb-nut 12 being mounted upon the end of the bolt and a spiral spring 13 being interposed between the supporting-post and magnet-yoke, thereby allowing the magnets to be moved toward or away from the armature by manipulating the thumb-nut.

The support for my resonator attachment comprises a rod or spindle 14, which is threaded for a considerable portion of its length and is supported in a horizontal position or parallel with respect to the base. In this instance I have shown this rod as provided with an angular bent portion 15, which is secured in the upper end of the supporting-post 11; but this rod may be supported upon the base in any other suitable manner. Mounted upon and freely movable on the threaded portion of the rod are a pair of bell-shaped or hemispherical drums or shells 16, their open ends facing each other and inclosed by the diaphragms 17, the hubs or sleeves 18 being inclosed within the shells and connecting the diaphragms and back of the shell. Thumb-nuts 19 are engaged upon the rod and form abutments for the outer faces of the shells, and a spring 20, interposed between the adjacent faces or diaphragms of the shells, forces the shells in engagement with the adjusting-nuts. The armature is caused to vibrate between the shells, striking the diaphragms of each, and it will be seen that by these means of the thumb-nuts the shells or resonators may be adjusted upon the spindle either with respect to each other or with respect to the armature.

The shells or resounding-chambers may be made of any suitable material—such as metal, hard rubber, wood, &c.—and the use of the two independent resounding-chambers greatly amplifies the sounds made by the in-

strument and renders the same very clear and distinct.

From the foregoing description, taken in connection with the drawings, it will be evident that I have accomplished all the objects herein set forth and have produced a practical resonator for telegraphic instruments.

Having thus described my invention, what I claim is—

1. The combination with a telegraph instrument, of a pair of spaced resonators mounted upon said instrument and adapted to be contacted by the armature thereof and tension means for spacing said resonators.
2. The combination with a telegraph instrument having a vibrating armature, of resonating-shells supported on each side of the armature and adapted to be contacted thereby means for changing the position of the shells, and automatic means for spacing the shells at the proper distance apart.
3. The combination with a telegraph instrument having a vibrating armature, of a support, resonating-shells arranged on said support on each side of the armature, means for independently adjusting the shells on the support with respect to each other, and tension means for spacing the shells.

4. The combination with a magnet and armature, of a support, drums arranged on the support on opposite sides of the armature, means for spacing the drums, and means for shifting the drums on the support.

5. The combination with a magnet and armature, of a support, resonating-shells arranged on the support, a spacing-spring between the shells, and means for shifting the shells on the support.

6. The combination with a telegraph instrument, of a support mounted thereon, hollow drums arranged on said support, adjustable abutments on said supports engaging the outer faces of the drums, and spacing means interposed between the drums.

7. The combination with a telegraph instrument, of a support mounted thereon, spaced resonators arranged on said support, adjustable abutments on the support engaging the resonators, and tension-spacing means interposed between the resonators.

In testimony whereof I have affixed my signature in the presence of two subscribing witnesses.

DENNIS A. WHITNEY.
